US00D754976S

(12) **United States Design Patent**
Harrington et al.

(10) **Patent No.:** **US D754,976 S**
(45) **Date of Patent:** **** May 3, 2016**

(54) **BRUSH HANDLE**

(71) Applicant: **Unger Marketing International, LLC**,
Bridgeport, CT (US)

(72) Inventors: **William Harrington**, Charlestown, RI
(US); **James M. Buckley**, New Hartford,
CT (US); **John A. Triunfo**, Fairfield, CT
(US)

(73) Assignee: **Unger Marketing International, LLC**,
Bridgeport, CT (US)

(**) Term: **14 Years**

(21) Appl. No.: **29/508,333**

(22) Filed: **Nov. 5, 2014**

Related U.S. Application Data

(63) Continuation-in-part of application No. 29/485,934,
filed on Mar. 25, 2014, now Pat. No. Des. 743,702.
